UNITED STATES PATENT OFFICE.

CHRISTIAAN DE JONGE, OF ZEELAND, MICHIGAN.

SILO-ROOF.

1,132,706.

Specification of Letters Patent. Patented Mar. 23, 1915.

Application filed November 19, 1913. Serial No. 801,782.

To all whom it may concern:

Be it known that I, CHRISTIAAN DE JONGE, a citizen of the United States, residing at Zeeland, in the county of Ottawa and State 5 of Michigan, have invented certain new and useful Improvements in Silo-Roofs, of which the following is a specification.

This invention relates to silos, and more especially to the roofs thereof, and it has 10 for one of its objects the provision of a roof which consists of a series of independently-pivoted interlocking sections, adapted to be opened upwardly so as to uncover the entire top of the silo.

15 The invention has, furthermore, for its object the combination with the roof sections, of a ventilator which is removable and which, when in place, will assist in keeping the several roof sections in closed 20 position.

25 The invention has also for its object the combination, with a series of roof sections which, when assembled and closed, will form a cone-shaped cover, of a plurality of fillers adapted to be interposed between and locked to the several roof sections when the latter are opened, thus increasing the capacity of the silo and also affording additional room for loading the same with 30 silage.

Further objects of the invention will hereinafter appear and be particularly defined in the claims.

The invention has been clearly illustrated 35 in the accompanying drawings in which similar characters denote similar parts, and in which—

Figure 1 is a top view of a silo having a roof embodying my invention. Fig. 2 is a 40 vertical section on line 2—2 of Fig. 1, the several roof sections being closed, and the ventilator in place. Fig. 3 is a similar section showing the roof sections opened out, and the fillers, above referred to, in proper 45 positions. Fig. 4 is an enlarged horizontal section of a portion of the silo roof on line 4—4 of Fig. 3. Fig. 5 is an enlarged horizontal section, fractionally, on line 5—5 of Fig. 2. Fig. 6 is a fractional top view of 50 the roof corresponding to Fig. 3, also on an enlarged scale.

Referring to the drawings, 10 denotes the wall of a silo which is made in circular form and of any desired material, and 55 capped with a sill 11 on which the roof is supported. In the present instance this

roof comprises a series of adjacent sections 12 of substantially truncated triangular form, having its side margins bent to form channeled flanges to interlock one another, 60 one of said sections serving as what may be termed a "key section" which, when in closed position, locks the entire roof against opening out. The several sections are pivoted on brackets 13 secured to the sill 11, 65 which latter may also be provided with an annular support member 14 against which the sections can come to rest as they are folded inward, one by one, to close the roof.

By considering the central line of Fig. 5 70 it is to be noted that the roof section member *c'* is the first one to be folded inward during the roof-closing operation. It will also be noted that this section has both of its marginal edges crimped to form similar 75 channels *a* which are adapted to receive, respectively, right and left hand flanges of a pair of adjacent fillers *f* (Fig. 4), the latter being used only when the roof sections are in their opened-out condition. After the 80 first section *c'* has been folded in, the next adjacent section *c''* is folded-in, bringing its right hand channel *b* over the channel-bend *a* of the section *c'*; while the channel formed on the left marginal edge of the section *c''* 85 corresponds to that shown at *d* on the right hand side of Fig. 5. In other words: all the sections, with the exception of the first closing section *c'* and the first opening section *c'*, have a narrow channel on their 90 right hand edges, while their left hand edges have wide channels sufficient to place over the narrow channels of the preceding section. This sequence of sections is maintained throughout, so as to fit them in place 95 until all the sections of the roof have been properly placed in position. It is also to be understood that any section may be provided with an opening through which the filling-pipe may be inserted for the silo, this 100 opening being normally closed by a glass *g* to admit light, if desired.

While in Fig. 5 a few roof sections have been illustrated in their closed-in condition, I have shown in Fig. 4 the same roof sections opened-out and the intervening space closed with the fillers above mentioned.

Fig. 6 represents a top view of the silo, and also shows the roof sections opened-out, with the fillers in place, and in order to 110 maintain the roof sections in their proper distended condition, and particularly to

brace them against outward pressure, I preferably employ clamping-bars 20, having their ends bent, as at 20', to straddle the crimped portions of a pair of adjacent roof sections; while at the inside of the silo, a bar 21 extends across the same sections, the two bars 20, 21 being drawn tightly together by clamping bolts 22, as is clearly illustrated in Fig. 6. In order to hold the fillers in position I preferably use a series of buttons 23, 24 pivoted to the opposite edges of each section respectively and extending in opposite directions, as clearly shown in Fig. 3. These same buttons may also be used to interlock the several roof sections when the latter are in closed-in condition, as clearly shown in Fig. 2, this construction naturally forming a substantial locking of the several sections.

In order to provide proper ventilation for the roof, I preferably employ a ventilator V having a collar 25, which is adapted to seat itself over all the upper ends of the closed-in sections, the body of the ventilator extending downwardly and carrying at its lower end a holding member 26 which may be slipped onto the end of said body after the ventilator is in place, and secured thereto as clearly shown in Fig. 2, in this manner still further locking the roof sections, and at the same time the ventilator, in position.

In recapitulation the manner of opening the roof is as follows:—Entrance having been gained into the interior of the silo through the filler-pipe opening, or otherwise, the member 26 is first removed from the ventilator which can then be pushed outward to release the upper ends of the roof sections; the several buttons 23, 24 are then disengaged, whereupon the first opening section o' is swung outward into vertical position. This will allow the second section o to be opened out in a similar manner. When these two sections are thus distended, a filler-plate f is inserted in place and buttoned. The process of opening the successive sections is then repeated until the last section c' has been reached and opened and held in place as above described. When the roof is to be closed the above described process is reversed, that is to say:—the section c' is the first one to be folded-in, and the section o' constitutes the last and final closing section.

Changes may be made in the particular construction of the several roof sections, as well as in the assemblage and the pivot support of the same, without departing from the spirit of the invention.

I claim:—

1. The combination with a silo, of a roof

therefor comprising a series of adjacent substantially triangular sections each having a channel in each of its side edges and adapted to be opened and closed relatively to the interior of the silo, means for pivotally supporting each section at its base on the silo-wall, and a series of independent removable fillers each having its sides bent to enter said channels for closing-in the open spaces between said sections when in opened-out position.

2. The combination with a silo, of a roof therefor comprising a series of adjacent substantially triangular sections adapted to be opened and closed relatively to the interior of the silo, means for pivotally supporting each section at its base on the silo-wall, a series of independent removable fillers for closing-in the open spaces between said sections when in opened-out position, and independent clamping devices engaging the opposite faces of said roof-sections and fillers, for holding the latter in position between said roof-sections.

3. The combination with a silo, of a roof therefor comprising a series of adjacent substantially triangular sections adapted to be opened and closed relatively to the interior of the silo, and having grooves at their adjacent sides, means for pivotally supporting each section at its base on the silo-wall, a series of removable fillers having flanges entering said grooves for closing-in the open spaces between said sections when in opened-out position between said roof-sections.

4. The combination with a silo, of a roof comprising a series of substantially triangular sheet metal sections adapted to be closed-in and opened-out, and having their margins bent to form inwardly-open channels, and a series of sheet metal fillers adapted to close the space between said sections when in open position, and having their edges outwardly bent to enter said section channels.

5. The combination with a silo, of a roof comprising a series of sections each having one of its side edges beneath the side edge of an adjacent section and having its other side edge above the edge of the other adjacent section, and a key section having both of its edges seated over the edges of the pair of adjacent sections.

In testimony whereof I affix my signature in presence of two witnesses.

CHRISTIAAN DE JONGE.
